UNITED STATES PATENT OFFICE.

FRANK R. PERRY, OF CHICAGO, ILLINOIS, ASSIGNOR OF ONE-HALF TO HARRY S. BENJAMIN, OF DETROIT, MICHIGAN.

PURIFYING APPARATUS FOR LUBRICANTS.

1,342,063.

Specification of Letters Patent. Patented June 1, 1920.

Application filed October 23, 1917. Serial No. 198,032.

To all whom it may concern:

Be it known that I, FRANK R. PERRY, a citizen of the United States, residing at Chicago, in the county of Cook and State of Illinois, have invented certain new and useful Improvements in Purifying Apparatus for Lubricants, of which the following is a description.

My invention belongs to that general class 10 of devices known as purifying apparatus and relates particularly to an apparatus designed for purifying oil used in lubricating hydrocarbon engines and the like. It may be mentioned, however, that its use is not 15 limited to lubricants for hydrocarbon engines as the same may be employed wherever found applicable. In the lubrication of hydrocarbon engines, in which in most types it is customary to provide a supply 20 of lubricant in the crank case, which is distributed by means of the splash, force feed, combined force and splash systems, or other arrangements, the lubricant may accumulate water, kerosene, gasolene or the like. 25 This is particularly so at the present time where low grades of hydrocarbons are used for the source of power. My device is intended to purify the lubricant by vaporizing and driving off the volatile particles, 30 water, kerosene, gasolene or the like, so that the lubricant deteriorates to a less extent. In this case it is unnecessary to drain the crank case as often as is now necessary at the present time. The invention has among 35 its objects the production of a device of the kind described that is simple, convenient, durable, compact, efficient and satisfactory for use wherever found applicable. My device may also be employed in connection 40 with the supplying of the hydrocarbon to the engine, thereby obviating the use of the type of vacuum feed commonly used for supplying gas or fuel from the fuel tank to the carbureter. Many other objects and ad- 45 vantages of the construction herein set forth will be obvious to those skilled in the art to which the same pertains.

To this end my invention consists in the novel construction, arrangement and combination of parts herein shown and described, and more particularly pointed out in the claims.

In the drawings, wherein like reference characters indicate like or corresponding 55 parts,

Figure 1 is a sectional view through my improved device illustrating its installation;

Fig. 2 is a sectional view through the same taken substantially on line 2—2 of 60 Fig. 1;

Fig. 3 is an enlarged sectional view through the device similar to a portion of Fig. 1, showing the valve open;

Fig. 4 is a sectional view taken substantially on line 4—4 of Fig. 5;

Fig. 5 is a sectional view taken substantially on line 5—5 of Fig. 2; and

Fig. 6 is a perspective view of the valve counter weight and supporting means. 70

Referring to the drawings, it may be mentioned that the device is shown installed on an internal combustion engine, 1 representing the crank case of the engine and 2 the exhaust pipe or the exhaust manifold. I 75 prefer to employ the exhaust pipe or manifold as a source of heat by means of which the water, gasolene, or kerosene and the like are vaporized and separated from the heavy and less volatile lubricating oil. My device 80 consists of the casing 3 of suitable size, shape and material, arranged to be secured on the exhaust pipe 2 or the like by means of the bolt 4 or equivalent means for the purpose. As shown the casing 3 is formed 85 to fit the exhaust pipe or manifold 2 so that heat is conducted through the wall of the casing to heat the contents of chamber A.

Arranged within the casing 3 is a tubular shell 6, open at the top and bottom, the top 90 edge being flanged as at 6' so as to overlie the top of the casing 3, packing 9, however, being arranged between the two. A cover plate 7 is also provided and arranged to be secured on the flange 6', packing material 10, however, being arranged between the two. The parts are secured together by the screws 8 or equivalent means for the purpose. The above sets forth the preferred method of assembling and securing together the parts, but as will be obvious from the further disclosure, this particular construction is not essential and the same 100 may be modified as preferred.

Arranged to coöperate with the lower 105 edge of the shell 6 is a valve member 11, the coöperating faces on valve 11 and shell 6 being such as to afford a tight fit when the valve is closed. I have shown lugs or parts 12 for guiding the valve, causing it to seat 110

properly when closed. The valve may be supported and controlled in any suitable manner.

As most clearly shown in Figs. 3, 4, 5 and 6, I provide a lever 14 pivotally mounted on a rod or support 15, the lever being provided with the counter weight 16 and connected by means of links 17 to a lug 13 on the valve. A pipe 18 is provided connecting with the chamber B in the shell 6 and is a vacuum pipe. The same may be connected with a vacuum pump driven by the engine or with the intake manifold or one of the cylinders. I have not considered it necessary, however, to illustrate this in detail, as such construction will be obvious, and in terming pipe 18 a vacuum or suction pipe the operation will be readily understood without entering into further detail.

A pipe 19 connects the lower part of the crank case below the normal oil or lubricant level with the chamber B, it being understood that any particular pipe fittings and the like may be employed for the purpose.

A vent opening or port 20 is provided for chamber A, and in the construction shown I form the opening 20 through the cover 7, flange 6' and part 1, and the intermediate packing or gaskets. Extending from adjacent the bottom of chamber A and opening into chamber B, is a duct, as shown a pipe 21, 22 being the port communicating with the chamber B. I also provide a pipe 23 projecting into the chamber A at the desired distance above the bottom thereof, which pipe is connected to the crank case 1 by means of the piping 24 and suitable fittings or the equivalents for the purpose. I also provide a pipe 25 in some cases, in communication with chamber B, the purpose of this pipe is to provide a vacuum in a fuel receptacle or auxiliary tank, whereby gasoline may be periodically drawn from the fuel tank to the auxiliary tank and then fed by gravity to the carburetor. Where such feed is not desired, as for example, in the case where the fuel tank is under the cowl in an automobile or above the engine, pipe 25 is unnecessary and the same may be omitted and its opening in the closure 7 plugged up. Obviously valves or their equivalent may be arranged as shown or as desired, valve 28 in pipe 18, valve 26 in pipe 19, valve 27 in pipe 24, valve 29 at vent 20, valve 30 at port 22, so that the several passages may be restricted or controlled as desired.

In Fig. 1, I have shown substantially diagrammatically a fuel feeding receptacle 60 consisting of the casing 31 and and inner casing 32, forming chambers 33 and 34, communication between the two being through pipe or port 35, at the end of which may be arranged valve 36. A vent 37 is also provided and a fuel intake pipe 38, 40

being the fuel discharge pipe connected with a carburetor 42 or the equivalent. Valves 39 and 41, etc., may be provided if desired. As shown, pipe 25 is connected with the chamber 34, 43 being a valve which 70 may be provided if desired.

The operation of the device may be briefly described as follows:—Assuming that the parts are in the positions shown in Fig. 1 and the engine not running. As the 75 engine is driven a vacuum is formed in pipe 18 and in chamber B, and the oil is drawn up through pipe 19 and discharged in chamber B. Any oil in chamber A above the lower end of pipe 21 and below the upper end of pipe 23 will also be drawn up into chamber B. Obviously air can enter port 20 to replace the oil drawn out of chamber A through pipe 21. As soon as the oil in chamber A has been drawn up into 80 chamber B air in chamber A passes through pipe 21 and the vacuum in chamber B is broken, there being atmospheric pressure in both chambers A and B. This being the case the weight of the oil in chamber B overcomes the weight 16, valve 11 opens and the 90 contents of chamber B are discharged into chamber A. A portion of the same will immediately flow through pipe 23 back to the crank casing. As soon, however, as the 95 chamber B is emptied or perhaps slightly before, the counter weight 16 will close valve 11 and the operation of the device will be repeated. In this manner oil is circulated from the crank case through my apparatus and back to the crank case. However, the oil is heated by the exhaust pipe 2 and the more volatile constituents or impurities, such as water, gasoline, kerosene and the like, are vaporized and driven off 100 and may escape through the port or vent 20. In this way, as the engine continues to run the oil is heated and purified. The device is particularly efficient and satisfactory in cold weather or at such times as some lubricants do not flow easily. However, in my device the lubricant is gradually warmed up and kept warm, and consequently is more efficiently circulated or splashed in the lubrication of the moving parts of the engine. 115

In case it is desired to bring the fuel from the fuel tank to the carburetor, pipe 25 is provided and connected to a suitable receptacle, which receptacle is connected to the 120 fuel tank and to the carburetor. A vacuum being periodically formed in chamber B it is likewise formed in the receptacle, and the fuel is thereby drawn into the receptacle and thence fed by gravity to the carburetor. 125 The so called vacuum tank or receptacle for the fuel may therefore be a simple device as formerly described, which will not easily get out of order or require attention and adjusting. 130

- The operation of the fuel receptacle or tank 31—32 will be obvious. A vacuum being created in chamber 34, fuel flows through pipe 38 into the receptacle, the 5 vacuum at the same time causing the valve 36 to be maintained closed. As soon as the vacuum is broken in pipe 25, however, the contents of chamber 34 are discharged into chamber 33 and may flow to the carbureter.
- 10 As soon as a vacuum is created again valve 36 is closed and more fuel is drawn into the chamber 34 from the fuel storage tank.
- Having thus described my invention, it is obvious that various immaterial modifications may be made in the same without departing from the spirit of my invention, hence I do not wish to be understood as limiting myself to the exact form, construction, arrangement and combination of parts 15 herein shown and described or uses mentioned.

What I claim as new and desire to secure by Letters Patent is:—

1. In a device of the kind described and in 25 combination, a receptacle, a vacuum pipe and a supply pipe connected therewith, a second receptacle below the level of the first, a valve controlling the flow of fluid from the first receptacle to the second, an air duct connecting the two receptacles from a point above the bottom of the first to a point below 30 the top of the second receptacle, a drain duct arranged to conduct fluid from the second receptacle, said second receptacle being 35 provided with an air duct communicating near the top thereof.

2. In a device of the kind described and in 40 combination, a receptacle, a vacuum pipe and a supply pipe connected therewith, a second receptacle below the level of the first, a counter-weighted valve controlling the flow of fluid from the first receptacle to the second, a duct connecting the two receptacles from a point above the bottom of the first to 45 a point below the top of the second, a drain duct arranged to conduct fluid from the second receptacle, said second receptacle being provided with an air duct communicating with the top thereof.

- 50 3. In a device of the kind described and in combination, a receptacle provided with a valve bottom, a counterweight therefor, a vacuum pipe and a supply pipe connected with said receptacle, a second receptacle 55 below the level of the first, an air duct connecting the two receptacles from a point above the bottom of the first to a point below

the top of the second, a drain duct arranged to conduct fluid from the second receptacle, said second receptacle being provided with 60 an air duct communicating with the top thereof.

4. In a device of the kind described and in combination, a receptacle, a vacuum pipe connecting therewith, and a supply pipe connected with a suitable source, a second receptacle below the level of the first, a valve controlling the flow of fluid from the first receptacle to the second, an air duct connecting the two receptacles from a point 70 above the bottom of the first to a point below the top of the second, a drain duct arranged to conduct fluid from the second receptacle back to the source, said second receptacle being provided with an air duct communicating near the top thereof.

5. In a device of the kind described and in combination, a receptacle, a vacuum pipe and a supply pipe connected therewith, a second receptacle below the level of the first, 80 a valve controlling the flow of fluid from the first receptacle to the second, an air duct connecting the two receptacles from a point above the bottom of the first to a point below the top of the second, a drain duct arranged 85 to conduct fluid from the second receptacle, said second receptacle being provided with an air duct communicating near the top thereof, and means for regulating the air duct.

6. In a device of the kind described and in combination, a receptacle provided with a bottom loosely seating on the margin thereof and operable to release the contents from the receptacle, a counter-weight arranged to 95 normally maintain the bottom in position to close the receptacle, a vacuum pipe and a supply pipe connected with the receptacle, a second receptacle below the level of the first, an air duct connecting the two receptacles from a point above the bottom of the first to a point below the top of the second, a drain duct arranged to conduct fluid from the second receptacle, said second receptacle being provided with an air duct communicating near the top thereof.

In testimony whereof I have hereunto signed my name in the presence of two subscribing witnesses.

FRANK R. PERRY.
